WINDOW CASEMENT CONSTRUCTION

John Brownlie, Freeport, and Ralph Gerstenzang, Brooklyn, N. Y., and Almon C. Blamey, Rutherford, N. J., said Blamey assignor to said Brownlie and said Gerstenzang

Application July 22, 1947, Serial No. 762,646

6 Claims. (Cl. 189—76)

1

This invention relates generally to casement construction and more particularly to window casement construction using metal frame elements.

Among the objects of the present invention lies the provision of window casement construction facilitating the assembly of vertical and/or horizontal muntins with the surrounding sash elements or frame.

Another object herein lies in the provision of a novel connecting element by the use of which metal window casements may be quickly and conveniently manufactured in large scale at low cost, so as to enjoy a consequent wide distribution and use.

Another object of the present invention lies in the provision of simplified assembly of the muntins to the sash frame without the use of any special tools or skill so that peening of tenons, riveting or welding, commonly used, are obviated.

Another object herein lies in the provision of construction of the class described wherein the integration of the parts provides a sturdy window casement which is sufficiently rigid for the purpose intended and yet which for the purposes of repair or otherwise, may be disassembled.

A feature of the invention lies in the fact that since muntins may be installed at any desired position along the length of the sash frame members by merely drilling a single hole at the point of connection of the muntin with the sash frame member, the window arrangement can be altered at the installation location to accommodate for different architectural effects.

A feature of the invention lies in the fact that by the use of the construction described, strong and serviceable window casements may be manufactured out of light weight metals such as aluminum or magnesium.

These objects and other incidental ends and advantages will more fully appear in the progress of this disclosure and be pointed out in the appended claims.

In the drawings in which similar reference characters designate corresponding parts throughout the several views:

Figure 1 is an enlarged fragmentary front elevational view of the juncture of one of the horizontal muntins of Figure 3 with the left hand vertical sash frame elements.

Figure 2 is a fragmentary vertical sectional view as seen from the plane 2—2 on Figure 1.

Figure 3 is a front elevational view of a window casement showing an embodiment of the invention.

2

Figure 4 is an elevational view of one of the connecting elements on the same scale as shown in Figures 1, 2 and 6.

Figure 5 is a fragmentary exploded view in perspective.

Figure 6 is a fragmentary horizontal sectional view as seen from the plane 6—6 on Figure 1.

In accordance with the invention, a metal window 10 is shown in Figure 3 as equipped with vertical side sash frame elements 11 and 12, a top sash frame element 13 and a bottom sash frame element 14. Secured to the vertical frame elements 11 and 12 are horizontal muntins 15 and 16. While we have shown only two horizontal muntins 15 and 16, obviously where desired any suitable number may be used, and while we have shown them to be horizontally arranged, where desired they may be vertically arranged. The present invention relates primarily to a novel means and manner of assembling the muntins to the frame element.

The frame element 11 and the frame element 12 are substantially identical except that one is arranged in a "left hand" position while the other is arranged in a "right hand" position. The frame element 11 includes a front member 17 having an inner edge 18 and an outer edge 19. Projecting rearwardly from the outer edge 19 is a rib 20. The element 11 also includes a rear member 21 having an inner edge 22 and an outer edge 23. Projecting forwardly from the edge 22 is the locking flange 24. The front member 17 and the rear member 21 are connected in spaced and parallel relationship by the inner and outer webs 25 and 26, respectively which are also spaced and parallel and arranged substantially at right angles to the members 17 and 21. The outer web 26, at the forward edge thereof, connects with the rear surface 28 of the front member 17 while the rear edge of the web 26 connects with the outer edge 23 of the rear member 21. The web 25 at the forward edge thereof is connected to the surface 28 of the front member 17 inwardly of the edge 18 so that the edge 18 projects to form a lip. The webs 25 and 26 are provided with orifices 29 and 30 of uniform and predetermined diameter. The orifices 29 and 30 are coaxially aligned.

The left end of the muntin 15 has a normal edge or terminal 32 which is substantially at right angles to the length of said muntins. The muntin 15 has a body 33, upper and lower vertical front flanges 34 and 35, upper and lower vertical rear flanges 36 and 37 and upper and lower horizontal rear flanges 38 and 39. The front flanges 34 and 35 and the rear flanges 36 and 37

are spaced and parallel and preferably perpendicular with respect to the body 33. The rear flanges 38 and 39 are preferably spaced and parallel to each other and the body 33. The terminal edge 32 is provided with a notch 40 having spaced and parallel side walls 41 and 42 and an inner wall 43 preferably parallel to the edge 32. The flanges 34 and 35 preferably extend the complete length of the body 33 while the rear flanges 36 and 37 stop short of the terminal edge 32 a distance substantially equal to or slightly greater than the distance between the outer face 44 of the inner web 25 and the outer surface 45 of the locking flange 24. The body 33 is provided with a locking indentation 46 having a forward wall 47, an inner wall 48 and an outer wall 49. The forward wall 47 is preferably spaced and parallel with the edge portion 50 of the body 33 and is spaced therefrom a distance substantially equal to the distance between the surface 51 of the locking flange 24 and the forward surface 52 of the rear member 21. The side walls 48 and 49 are preferably parallel and spaced from each other a distance substantially equal to the distance between the outer surface 45 and the inner surface 152.

The connecting element 53 includes a head 54 and a bifurcated shank 55, the legs of which have opposed parallel inner surfaces 56 and 57, the outer ends of which are chamfered at 58 and 59 (see Figure 4). The head has a plurality of teeth 60 which are spaced and parallel to each other and extend around the head 54 parallel to the longitudinal axis of the connecting element 53. The tip circle of the teeth 60 is of greater diameter than the diameters of the orifices 29 and 30 so that the lands of said teeth may cut into the borders of the orifices 29 and 30 to become frictionally secured against movement in a longitudinal direction with respect to the connecting element. Rotation of the head is prevented by the teeth 60 cutting their own grooves in the borders of the orifices 29 and 30.

The assembly of the device is a simple and convenient matter. The distance between the edge 50 and the forward surface 61 of the flanges 34 and 35 is less than the distance between the inner surface 52 and the rear surface 62 of the lip 18 by an amount equal to the distance which the locking flange 24 projects forwardly from the surface 52. This enables the horizontal muntin 15 to be brought in a left hand direction as viewed in Figure 6, for example, only the edge 32 meets the outer face 44 of the inner web 25, whereupon the muntin 15 may be moved rearwardly until the surface 50 contacts the surface 52. The body 33 is aligned so that its longitudinal axis is in substantial alignment with the axes of the orifices 29 and 30. Next, the connecting element is inserted through the orifices 39 and 29 so that the chamfered edges 58 and 59 engage the upper and lower edges of the inner wall 43. Following this suitable force is applied upon the surface 63 of the head 54 in an axial direction so as to force the surfaces 56 and 57 to engage the upper and lower surfaces respectively of the body 33. The length of the head 54 is preferably such that when fully seated the surface 64 of the head 54 abuts against the inner wall 43 while the surface 63 becomes flush with the outer surface 65 of the outer web 26. Thus, the inner portion of the head 54 (on the right hand as viewed in Figure 6, for example) prevents forward movement of the muntin 15.

As will be obvious to those skilled in the art corresponding construction and engagements may

be utilized on the right hand end of the muntin 15 or on upper and lower ends of vertically arranged muntins. Where it is desired to remove a muntin for repair purposes or otherwise it becomes necessary only to exert sufficient pressure outwardly of the device 10 upon the inner tips of the bifurcated legs of the shank 55. When the connecting element is fully seated, upward and downward movements of the muntin 15 are prevented by the shank 55; movement of the muntin rearwardly or outwardly of the device 10 is prevented by the abutment of the edge 50 and wall 47, and the terminal edge 32 against the surfaces 52 and 51, and 44 respectively; movement of the muntin 15 inwardly of the device is prevented by the wall 49 abutting against the surface 152 of the locking flange 24; and movement of the muntin 15 forwardly of the device is prevented by the wall 41.

Glazing of the finished casement may be performed in any usual manner, as for example, by the use of putty.

We wish it to be understood that we do not desire to be limited to the exact details of construction shown and described for obvious modifications will occur to a person skilled in the art.

We claim:

1. Window casement construction comprising: a sash frame element including an elongated web, a member extending at an angle with respect to said web and having a locking flange; a muntin element including a body with a terminal edge and a longitudinally arranged edge; said terminal edge having a notch, and said longitudinally arranged edge having an indentation; said indentation being engageable with said locking flange; and connecting means joining said web with said body at said notch; said connecting means including a connecting element having a head penetrating said web and a bifurcated portion straddling said body at said notch.

2. In a window casement construction including a sash frame element, and a muntin element engaged with said sash frame element, the improvement comprising: a bifurcated pin, one portion of which engages the sash frame element, and the bifurcated portion of which straddles the muntin element.

3. In a window casement construction including a sash frame element and a muntin element, the improvement comprising: said muntin element including a body having an end edge with a notch therein; a connecting element having a pair of legs and a head; said sash frame element including an elongated web; said head penetrating said web, and said legs straddling the body at the notch, thereby preventing lateral motion of said body with respect to said frame element.

4. In a window casement construction including a sash frame element having an orificed elongated web and a muntin element having a body with a terminal edge, the improvement comprising: a connecting element having a head portion and a bifurcated portion, said head portion having a roughened exterior and penetrating said web, said bifurcated portion straddling said body which is frictionally engaged therebetween.

5. A device as claimed in claim 4 in which the roughening of the head portion is in the form of a series of radially extending teeth.

6. Window casement construction comprising: a sash frame element including a web; a front member projecting from said web and forming a lip; a rear member extending at an angle from said web and having a locking flange which is

substantially forwardly directed; a muntin element, the width of which, at the end thereof, is not greater than the spacing between the forward surface of said locking flange and the surface of the lip opposed to the locking flange in a direction substantially parallel with the plane of said web; said muntin element having a body provided with an indentation engageable with said locking flange; whereby said muntin element is insertable between said lip and said member on the sash frame element by a movement in a lateral direction with respect to said web and then rearwardly to engage the locking flange with the said indentation.
